UNITED STATES PATENT OFFICE.

LUDVIK RASCH, OF OSLO, NORWAY, ASSIGNOR TO A/S. FJELDBOR, OF OSLO, NORWAY.

ROTATING HAMMER.

Application filed April 1, 1925. Serial No. 20,016.

To all whom it may concern:

Be it known that I, LUDVIK RASCH, engineer, a subject of the King of Norway, residing at Stortingsgaten 14, Oslo, Norway, have invented new and useful Improvements in Rotating Hammers, of which the following is a specification.

The present invention relates to rotary hammers of the kind, wherein an eccentrically pivoted hammer body is flung against an abutment by means of centrifugal force or hammering member and is then thrown back by the striking force, so that the hammer body gets clear of the said member and may again be flung forwardly against the same.

Experience has shown that in rotary hammers of this type the vibrations produced in the rotary carrier of the hammer body during the reciprocating motion of said body have had a detrimental influence upon the carrier.

The present invention has for its object to remove this detrimental influence by providing a suitable braking effect of the hammer body motion relatively to the carrier both during its backward throw and during its travel towards the hammering member.

Such a braking effect may suitably be produced by causing the hammer body to move within a compartment enclosing the hammer body sufficiently tightly to prevent the free escape of air therefrom at the rear side of the hammer body. Consequently a shock absorbing air cushion is formed between the bottom of the compartment and the hammer body. The braking effect taking place during the driving stroke in such an embodiment will also arise under special conditions. For if care is taken that the air is not quite enclosed within the said compartment but is able to escape with a limited velocity, the compartment will contain a quantity of air of a definite pressure dependent upon the escaping velocity. During the driving stroke the access of air to the chamber will now be made difficult, because the hammer body fills out substantially the whole cross section of the compartment, and at the rear side of the hammer body a rarefaction of air will take place adapted to cause a braking influence during the forward throw of the hammer body, until the latter at a suitable distance from the abutment gets clear of the said compartment. The rotation of the carrier in combination with

oscillation of the hammer body relatively to the rotating carrier will result in the hammering member being hit with the desired striking force.

The explained braking method has in this connection also the advantage as to enable an easy regulation, either by adjusting the air passage to and from the said air compartment or by varying the effective volume of the air compartment by means of an adjustable auxiliary compartment.

A preferred embodiment of the invention is illustrated in the annexed drawing showing in Figure 1 diagrammatically a cross sectional view of a hammer device constructed in accordance therewith. Figure 2 is a part of a similar view showing a modification.

In the drawing 1 represents the boring machine casing, 2 its carrying handle and 3 its knocking or hammering member. 4 is a carrier pivoted concentrically in the casing 1 and provided with a pivot 6 mounted eccentrically with regard to the casing and forming the carrying pin of the oscillatory hammer body 5, within the carrier 4 a compartment 7 is arranged, the cross section of which is substantially filled out by the hammer body during its motion. 8 represents the bottom of the compartment and 9 an additional or auxiliary compartment communicating with the compartment 7 and the volume of which may be varied for instance by a screw stopper 10 filling it more or less. If now the hammer body is flung back from the striking position shown in full lines, it will move freely until its upper edge covers the upper edge of the compartment 7 whereupon an air compression will take place on the rear side of the hammer body resulting in a softening of the stroke during the motion towards the position indicated in dotted lines, wherein the hammer body is about to be flung forwardly again. During the motion in opposite direction the hammer body is braked on account of the air rarefaction taking place within the compartment 7 behind said body and when the hammer body gets out from this compartment, it will be caused, as a consequence of its combined motion, to strike the hammering member 3 with a sufficient velocity to produce the desired striking effect upon the same.

By varying the volume of the additional compartment obviously a variation in the braking effect is obtained both during the

return stroke and during the driving stroke of the hammer body.

Instead of effecting the regulation by means of an additional compartment 9, an adjustable air valve 11 (Figure 2) may be arranged in combination with the compartment 7 in such a manner that the adjustment takes place by controlling the air passage from and to the said compartment, 10 when the hammer body moves back and forward therein, the adjustment taking place preferably by a needle valve.

Having now particularly described and ascertained the nature of my said invention 15 and in what manner the same is to be performed I declare what I claim is:

1. In a rotary hammer, the combination of a casing, a hammering member movably arranged therein, a rotating carrier arranged concentrically within the casing, a hammer body pivotally connected with the carrier excentrically to its rotating axis so as to strike against a portion of the hammering member once for each revolution of the 25 carrier, an inwardly closed compartment arranged in the carrier so as to receive the inwardly moving hammer body in its retracted swinging position, the said body substantially filling out the cross section of 30 the compartment, the air contained in the compartment acting thereby as an air cushion during the inward motion of the hammer body.

2. In a rotating hammer, the combination 35 of a casing, a hammering member movably arranged therein, a rotating carrier arranged concentrically within the casing, a hammer body pivotally connected with the carrier excentrically to its rotating axis so as to strike against a portion of the hammering member once for each revolution of the carrier, an inwardly closed compartment arranged in the carrier so as to receive the inwardly moving hammer body in its retracted swinging position, the said body substantially filling out the cross section of 40 the compartment, means for controlling the air pressure prevailing in said compartment and acting upon the motion of the hammer body therein.

3. In a rotary hammer, the combination 55 of a casing, a hammering member movably arranged therein, a rotating carrier arranged concentrically within the casing, a hammer body pivotally connected with the carrier excentrically to its rotating axis so as to strike against a portion of the hammering member once for each revolution of the carrier, an inwardly closed compartment arranged in the carrier so as to receive the inwardly moving hammer body in its retracted swinging position, the said body substantially filling out the cross section of 60 the compartment, means adjustably controlling the air pressure prevailing in said com-

partment and acting upon the motion of the hammer body therein.

4. In a rotary hammer, the combination of a casing, a hammering member movably arranged therein, a rotating carrier arranged 70 concentrically within the casing, a hammer body pivotally connected with the carrier excentrically to its rotating axis so as to strike against a portion of the hammering member once for each revolution of the 75 carrier, an inwardly closed compartment arranged in the carrier so as to receive the inwardly moving hammer body in its retracted swinging position, the said body substantially filling out the cross section of 80 the compartment, an additional compartment being in communication with the first mentioned compartment for controlling the air pressure therein during the motion of the hammer body therein, the air contained 85 in the compartments acting thereby as an air cushion during the inward motion of the hammer body.

5. In a rotating hammer, the combination 90 of a casing, a hammering member movably arranged therein, a rotating carrier arranged concentrically within the casing, a hammer body pivotally connected with the carrier excentrically to its rotating axis so as to strike against a portion of the hammering member once for each revolution of the carrier, an inwardly closed compartment, arranged in the carrier so as to receive the inwardly moving hammer body in its retracted swinging position, the said body substantially filling out the cross section of 95 the compartment, an additional compartment being in communication with the first mentioned compartment, means for adjusting the volume of the additional compartment, for the purpose of enabling a regulation of the softening influence of the main compartments upon the hammer motion.

6. In a rotary hammer, the combination 100 of a casing, a hammering member movably arranged therein, a rotating carrier arranged concentrically within the casing, a hammer body pivotally connected with the carrier excentrically to its rotating axis so as to strike against a portion of the hammering member once for each revolution of the carrier, an inwardly closed compartment arranged in the carrier so as to receive the inwardly moving hammer body in its retracted swinging position, the said body substantially filling out the cross section of 110 the compartment, an additional compartment communicating with the inner part of the main compartment, and provided with an adjustable bottom for the purpose of varying the total volume of the compartments and thereby also varying their softening influence upon the motion of the hammer body.

7. In a rotary hammer, the combination 115

of a casing, a hammering member movably arranged therein, a rotating carrier arranged concentrically within the casing, a sector-shaped hammer body pivotally connected by its hub portion with the carrier eccentrically to its rotating axis so as to strike against a portion of the hammering member once for each revolution of the carrier, an inwardly closed compartment arranged in the carrier so as to receive the inwardly moving hammer body, the outer limiting surface of the compartment being concentrical to the hub of the hammer body, the said body substantially filling out the cross section of the compartment, the air contained in the compartment acting thereby as an air cushion during the inward motion of the hammer body.

8. In a rotary hammer, the combination of the casing, a hammering member movably arranged therein, a rotating carrier arranged concentrically within the casing, a sector-

shaped hammer body pivotally connected by its hub portion with the carrier eccentrically to its rotating axis so as to strike against a portion of the hammering member once for each revolution of the carrier, an inwardly closed compartment arranged in the carrier so as to receive the inwardly moving hammer body, the outer limiting surface of the compartment being concentrical to the hub of the hammer body, the said body substantially filling out the cross section of the compartment, an additional compartment communicating with the inner part of the main compartment and provided with an adjustable bottom for the purpose of varying the total volume of the compartments and thereby also varying their softening influence upon the motion of the hammer body.

In witness whereof I affix my signature.

LUDVIK RASCH.
